United States Patent Office

Des. 221,357
Patented Aug. 3, 1971

221,357

TYPEWRITER

Richard H. Penney, New York, N.Y. assignor to
Sperry Rand Corporation, New York, N.Y.

Filed Aug. 11, 1969, Ser. No. 18,618

Term of patent 14 years

Int. Cl. D18—01

U.S. Cl. D64—11

FIG. 1.

FIG. 2.

FIG. 3.

FIG. 4.

FIG. 5

FIG. 1 is a front perspective view of a typewriter showing my new design;

FIG. 2 is a right elevational view thereof, the left side being similar in appearance;

FIG. 3 is a rear elevational view;

FIG. 4 is a top view; and

FIG. 5 is a front elevational view.

I claim:

The ornamental design for a typewriter, substantially as shown and described.
